STITCH-FORMING MECHANISM FOR SHOE-SEWING MACHINES.

1,194,514.

Specification of Letters Patent. Patented Aug. 15, 1916.

Original application filed May 29, 1914. Serial No. 841,752. Divided and this application filed March 25, 1915. Serial No. 17,046.

To all whom it may concern:

Be it known that I, OSCAR L. LAWSON, a subject of the King of Sweden, residing at Lynn, county of Essex, State of Massachusetts, have invented a certain new and useful Improvement in Stitch-Forming Mechanism for Shoe-Sewing Machines, of which the following is a specification, reference being had therein to the accompanying drawings.

10 This is a division of my prior application Serial Number 841,752, filed May 29, 1914, for Lock stitch sewing machine.

This invention relates to sewing machines for leather work, and has particular reference to the loopers for a sewing machine of the character described.

My improvements are designed with special reference to providing a sewing machine which will be of low cost and effective 20 for use by cobblers as well as for the general purposes to which leather sewing machines are put.

The particular object of my invention is to provide improved mechanism for laying 25 the thread in the hook of the needle.

The mechanism shown and described herein may be operated by a single cam but gives to the thread the requisite motions and therefore results in greatly simplifying the 30 construction of the machine in which it is embodied, making it possible to produce an efficient machine at a very small expense.

The invention will be fully understood by reference to the following specification, 35 taken in connection with the accompanying drawings, and the novel features thereof are pointed out and distinctly defined in the claims at the close of this specification.

In the accompanying drawings, Figure 1 40 is a detail side elevation of the stitch forming mechanism and the mechanism for laying the thread in the hook of the needle together with the cam and the operating mechanism therefor. Figs. 2 and 3 are detail 45 front elevations of the mechanism for laying the thread in the hook of the needle, said two figures illustrating the parts in different positions. Fig. 4 is an elevation looking from the left of Fig. 2. Fig. 5 is a plan 50 view looking down from line 5—5 in Fig. 3.

Similar reference characters indicate the same or similar parts in all the views.

In the drawings, at 30 is shown the work

support; at 31 the hook needle; at 33 is shown the segment to which the needle is secured. The awl is shown at 32 and it is to be understood that the machine is of the type known as "awl-feed," that is, by suitable mechanism not necessary to describe or illustrate in detail, the awl passes through a slot in the work support and is shifted when in upper position so as to feed the work along. These parts are in general old and well known and are further described in my prior application to which reference has heretofore been made.

The means for laying the thread in the hook of the needle when the latter is in the lower position, that is, the position shown in Fig. 4, consists in a tubular guide or looper 68 and a hook 69, carried respectively by the arms or levers 70 and 71, pivoted at 72 to a block 73 pivotally mounted or hung upon a pin 74 carried by an arm 75, which is pivotally supported at 76 by the frame of the machine. The pivotal connection 72 between the levers and the block 73 is such that said levers are held against the base of the block so that while they may oscillate relatively to each other on the pivot 72 they will follow all the swinging motions of the block 73.

A lever 77 pivotally supported at 78 and pivotally connected at 79 to the block 73 has a roll 80 which is engaged by a suitably formed cam groove in the side of the disk 58. As the lever 77 is moved up and down by the cam its own pivotal connection, and the pivotal connection with the block 73 and the support of the latter by the swinging arm 75 result in the guide or looper 68 and hook 69 having the following motions:—It being understood of course that the thread which is to be engaged by the hook needle is permanently in the tubular guide or looper 68 and the first stitch having been made by the operator holding the end of the thread, or it being assumed that one or more stitches have already been made, then as the needle passes down through the slot of the work support the said guide or looper and hook move upwardly. At the same time the hook shifts across the top of the guide and moves laterally to the position shown in Fig. 2, so as to stretch a portion of the thread substantially horizontally.

behind the needle, the guide and hook then shifting slightly forward to lay the thread in the needle hook.

I will now describe the mechanism which causes the two levers to swing relatively to each other from the position shown in Fig. 1 to the position shown in Fig. 2:—The lower ends of the levers 70 and 71 are formed with extensions or cam lugs 81, 82 respectively, said lugs extending down between two fixed guide pins 83 projecting from a frame bracket 84. The sides of the lug 81 are preferably straight and parallel; the lug being slightly inclined to one side the lug 82 having its sides curved and inclined more than the lug 81 and in a direction opposite the inclination of the lug 81. This is in order to impart considerably more lateral movement to the hook 69 than to the guide 68. As the block 73 is shifted up and down, the lugs 81 and 82 slide between the fixed pins 83 projecting from the frame bracket 84, and cause the guide 68 and hook 69 to follow the paths described, or reach the positions indicated in the drawings.

Assuming that the guide and hook occupy the position shown in Fig. 1 and the sewing operation then proceeding, the levers begin to rise with the guide and hook both shifting to the rear as they move upwardly. The hook then moves across the top of the guide toward the position shown in Fig. 3, then continues to the position shown in Fig. 2. Just before reaching the last mentioned position, the swing of the block 73 is such that the guide and hook move forwardly and lay the thread in the hook of the needle. The needle then begins to rise and the guide and hook retreat toward and to the position shown in Fig. 1.

From the foregoing it will be seen that the oscillating or opening and shutting movement of the guide or looper 68 and hook 69 as well as the swinging movement of the said members about the pivots 74 and 76 are produced wholly by the movements of the single cam on the disk 58, and that therefore a simple and inexpensive but effective mechanism is provided for laying the thread in the hook of the needle.

What I claim is:

1. A looper mechanism for a hook needle sewing machine comprising a pivotally supported block, a pair of arms pivotally connected to said block, one arm having a thread guide, and the other having a hook, means for raising and lowering the block and swinging it to shift the guide and hook to and from juxtaposition to the path of the needle hook to present the thread in position to be engaged by the needle hook, and

means for swinging said arms on their pivots as they rise and descend with the block.

2. A looper mechanism for a hook needle sewing machine comprising a pivotally supported block, a pair of arms pivotally connected to said block, one arm having a thread guide, and the other having a hook, means for raising and lowering the block and swinging it to shift the guide and hook to and from juxtaposition to the path of the needle hook, said arms having cam portions, and fixed members between which said cam portions slide, whereby the thread is presented to a position to be engaged by the hook of the needle and is then spread to draw out the thread for formation of a loop by movement of the needle.

3. A looper mechanism for a hook needle sewing machine comprising a pivotally supported block, a pair of arms pivotally connected to said block, one arm having a thread guide, and the other having a hook, means for raising and lowering the block and swinging it to shift the guide and hook to and from a position in a plane in juxtaposition to the path of the needle hook to present the thread to be engaged by the needle hook, said arms having diverging lower ends, and fixed pins between which said ends slide, to spread apart the guide and hook and draw out the thread for formation of a loop after it is engaged by the needle hook.

4. A looper mechanism for a hook needle sewing machine comprising a pivotally supported block, a pair of arms pivotally connected to said block, one arm having a thread guide, and the other having a hook, means for raising and lowering the block and swinging it to shift the guide and hook to and from a position in a plane in juxtaposition to the path of the needle hook to present the thread for engagement by the needle hook, said arms having diverging lower ends, and fixed pins between which said ends slide, the lower end of the arm having the hook being curved, the lower end of the other arm being substantially straight, to spread apart the guide and hook and draw out the thread for formation of a loop by the hook when the block moves upward and then to move the guide and hook again toward each other when the block moves downward.

In testimony whereof I affix my signature, in presence of two witnesses.

OSCAR L. LAWSON.

Witnesses:

GEORGE P. DIKE,

ALICE H. MORRISON.
